UNITED STATES PATENT OFFICE.

CLARENCE I. BAKER, OF ELIZABETH, NEW JERSEY, ASSIGNOR TO WESTERN ELECTRIC COMPANY, INCORPORATED, OF NEW YORK, N. Y., A CORPORATION OF NEW YORK

CALLING DIAL.

Application filed March 7, 1924. Serial No. 697,460.

To all whom it may concern:

Be it known that I, CLARENCE I. BAKER, a citizen of the United States of America, residing at Elizabeth, in the county of 5 Union, State of New Jersey, have invented certain new and useful Improvements in Calling Dials, of which the following is a full, clear, concise, and exact description.

This invention relates to calling dials, 10 and more specifically to calling dials of the type used in automatic telephone exchanges for controlling the movement of automatic switches and the like.

An object of the invention is to reduce 15 to a minimum the false operation of the shunt springs of a calling dial and the resultant setting of the telephone circuit through the accidental operation of the finger wheel.

20 These objects are accomplished by providing means permitting a limited movement of the dial before the shunt springs are operated to their off-normal position, and by providing for maintaining the shunt 25 springs in their off normal position, when once operated, until the switching operations are completed and the dial returned to its normal position.

Another feature is the arrangement of 30 parts whereby the mechanism for operating the impulse springs of the dial is rendered more compact.

Other features of the invention and advantages will appear from the following 35 description and the claims appended hereto, reference being had to the accompanying drawings in which Fig. 1 is a plan view of the calling dial with the finger wheel and casing partially cut away so as to show the 40 impulse mechanism more clearly; Fig. 2 is a vertical sectional view taken approximately on line 2—2 of Fig. 1; Fig. 3 is a horizontal sectional view taken approximately on line 3—3 of Fig. 2 and viewed in 45 the direction indicated by the arrows, and Fig. 4 is a view similar to that of Fig. 3, but showing the shunt spring operating member out of normal position. Similar reference characters refer to similar parts 50 throughout the several views.

The calling dial shown in Fig. 1 consists of a casing 10 in which the plates 11 and 12 are secured by means of a number of screws 13. On plate 11 is rigidly fastened 55 a bushing 14 in which the shaft 15 is loosely

mounted. On the top end portion of shaft 15 there is mounted a finger wheel 16 which is held securely thereon by means of a screw 9 or any other suitable means.

The motor spring 18 is hooked on a cup-shaped disc 17 and a lug 19 which is integrally formed with the stationary plate 12. The shaft 15 has a collar 20, the periphery of which is provided with a plurality of notches 21 which register with the keys 60 22 of the cup-shaped disc 17 adapted for adjusting the tension of the motor spring 18 and for holding it in position concentric with reference to the shaft 15. On the lower end portion of bushing 14 there is 65 rotatably mounted a gear 23 which has a toothed clutch portion 24 in operable relation with its complementary clutch member 25 which is mounted on the shaft 15 and secured thereon by means of a nut 49 and 70 an arm 48 which is provided for a purpose which will be hereinafter described. Gear 23 meshes with a pinion 26 which is loosely mounted on a spindle 27 secured on bracket 28 which is preferably formed integral with 75 the plate 11. On the hub portion of pinion 26 there is secured a gear 29 which meshes with a pinion 30 loosely mounted on the upwardly extending portion of bushing 14. Pinion 30 carries, at one end, an impulse 80 cam 31 which is made of insulating material and on the other end a worm gear 32 which meshes with the worm 33 secured on the shaft 34 of a centrifugal governor 35 which may be of any well known type. 85

The shunt springs 39, 40 and 41 and the impulse springs 37 and 38 are mounted on the plate 11 in the form of a bank 8. The functions of these springs will be understood by reference to F. N. Reeves' Patent 95 No. 1,353,612, granted September 21, 1920, which shows a circuit in which a dial embodying this invention may be used. The terms "shunt springs" and "impulse 100 springs" as used herein are intended to be generic terms embracing calling mechanism operated contacts having functions equivalent to those of Reeves' contacts. The impulse springs 37 and 38, extend from the bank in operable relation with the impulse 105 cam 31 which is geared to operate the impulse springs once for each revolution. Integrally formed with the shunt spring 40 there is provided an arm 42 which extends 110 downwardly therefrom in operable relation

with a camming member 43. This member 43 is secured on one end of a pivot 7 which is loosely mounted in a bushing 44, secured in the plate 11. On the opposite end of pivot 7 there is securely arranged a toothed member 45 which is provided with a notch 46 adapted to cooperate with a stop 47 and the arm 48 for holding the finger wheel 16 in normal non-operated position against the resistance of motor spring 18, and for limiting the movement of the camming member 43.

In casing 10 there is mounted a disc 50 adapted for supporting a numbered disc 51 which is held securely thereon by means of a removably arranged ring 52 interposed between the ridge 53, of disc 50 and the numbered disc 51. The tension of the motor spring 18 may be adjusted by disengaging the disc 17 from the notches 21 of collar 20 and rotating this disc on the shaft 15 until the proper tension of the spring is secured.

The operation of the dial is as follows: Supposing that it is desired to send a series 25 of electrical impulses through a telephone or similar circuit, the movement of the finger wheel 16 toward the stationary finger stop 53 in a clockwise direction rotates the arm 48 which moves the toothed member 45 and the camming member 43 carried thereby in position shown in Fig. 4 for establishing contacts between the shunt springs 40 and 41 and wind the motor spring 18. But it is to be noted that due to the space 30 between the arm 48 and tooth 54 of member 45, the finger wheel 16 and arm 48 carried thereby, are free to move a sufficiently great angular distance ineffective with respect to the shunt spring 40 in order to prevent the accidental setting of a selector switch in case the finger wheel 16 is permitted to return to normal before the dialing operation. The rotation of the finger wheel 16 and the clutch member 25 carried thereby in a counter-clockwise direction, engages the clutch toothed portion 24 of gear 23 which rotates as a unit with the shaft 15 under the action of the motor spring 18. Gear 23 rotates the pinion 26 which transmits its movement to the gear 29 through the hub portion 6. Gear 29 rotates the pinion 30 and the impulse cam 31 carried thereby for operating the impulse springs 37 and 38 at each revolution of the cam. The worm gear 32 carried 45 by pinion 30 rotates the centrifugal governor 35 adapted for controlling the speed of the impulse cam. When the finger wheel 16 and the arm 48 reach a very small angular distance from normal in its return movement, the arm 48 engages the tooth portion 49 of member 45 for operating the shunt spring 40 at the instant the finger wheel reaches its normal position.

What is claimed is:

60 1. In a calling dial, an impulse mecha-

nism, a finger wheel for actuating said mechanism, shunt springs, and means operable through the movement of said finger wheel for opening and closing said springs at different angular distances according to the 70 direction of movement of said finger wheel.

2. In a calling dial, the combination with a casing, of an impulse mechanism, a removably arranged plate in said casing for supporting said mechanism, a finger wheel, a 75 spring tensioned by the movement of said wheel for operating said mechanism, operable shunt contacts, and a camming member operable for closing and opening said contacts at different angular distances with reference to the movement of said wheel in different directions.

3. In a calling dial, a casing, a removably arranged plate in said casing, an impulse mechanism arranged on said plate, said 85 mechanism including a shaft, a finger wheel secured on said shaft, means carried by said shaft for operatively engaging said mechanism through the movement of said wheel in one direction, shunt contact springs, and 90 means operable through the movement of said wheel for opening and closing said shunt springs at different angular distances with reference to the normal position of said finger wheel.

4. In a calling dial, the combination of a casing, an impulse mechanism, a plate arranged in said casing for supporting said mechanism, a finger wheel, a motor spring wound by the movement of said wheel in one 100 direction for actuating said mechanism, shunt springs, means operable through the movement of said wheel for operating said shunt springs and a stop in said casing co-operating with said means for holding said 105 wheel in normal non-operated position.

5. In a calling dial, the combination of a casing, an impulse mechanism arranged therein, a centrally disposed rotatable shaft, a finger wheel arranged on said shaft, a 110 motor spring arranged to be tensioned through the movement of said wheel for actuating said mechanism, a stop for said finger wheel, shunt springs, and means for opening and closing said shunt springs at 115 different distances from said stop.

6. In a calling dial, the combination of a casing, a removably arranged plate in said casing, impulse and shunt contact springs arranged on said plate, a mechanism for operating said impulse springs, said mechanism consisting of a rotatable shaft, a finger wheel arranged on one end of said shaft, a motor spring, a gear train, a cam actuated by said gear train for operating 120 said impulse spring through the tension of said spring, a clutch member carried by said shaft for operatively engaging said gear train, and means operable through the movement of said finger wheel for opening and 125 130

closing said shunt springs at different angular distances depending upon the movement of said wheel.

7. In a calling dial, an impulse mechanism, said mechanism including a finger wheel, a gear train, a cam actuated by said gear train, a pair of impulse contacts operable through the movement of said cam, a speed governor for controlling the movement of said gear train, a motor spring tensioned through the movement of said finger wheel in one direction for actuating said gear train in the other direction, shunt contacts, and means carried by said shaft for 10 opening and closing said shunt contacts in

different angular distances upon the movement of said wheel in different directions.

8. In a calling mechanism for telephones, an operating member having a forward and a backward movement, impulse mechanism 20 operated on said backward movement, and a contact operated at an interval after the beginning of said forward movement and remaining in operated position substantially until the end of said backward movement. 25

In witness whereof, I hereunto subscribe my name this 29th day of February A. D., 1924.

CLARENCE I. BAKER.
